UNITED STATES PATENT OFFICE

2,362,313

AUXILIARY SWITCH

Harold N. Schneider, Philadelphia, Pa., assignor
to General Electric Company, a corporation of
New York

Application March 29, 1943, Serial No. 480,941

5 Claims. (Cl. 200—5)

My invention relates to an auxiliary switch for an electric circuit breaker which switch is opened and closed in response to the position of the circuit breaker.

Auxiliary switches associated with circuit breaker mechanisms have been used extensively heretofore. Most of these switches are closed and opened at the same point during the circuit breaker closing and opening strokes. For high speed reclosing type circuit breakers it would be desirable to have an auxiliary switch which completes the trip circuit insofar as the auxiliary switch is concerned at a given point during the closing stroke of the circuit breaker and which opens the trip circuit at an entirely different point during the opening stroke of the circuit breaker. If the circuit breaker is closed on a fault an arc is likely to strike when the contacts are still separated by a sizable proportion of the entire stroke. Consequently it is desirable to have the trip circuit completed early during the closing stroke so that opening of the circuit breaker in the event of closing on a fault may occur very early during the closing stroke and long before the contacts are completely closed. Similarly, it is desirable to have the contacts of the auxiliary switch opened early during the opening stroke so that the contacts of protective relays and the like if sealed in by the tripping current may reset to be ready to again properly control the trip circuit upon immediate reclosing of the circuit breaker. Also, if the particular circuit breaker with which the auxiliary switch is associated happens to be the well-known air blast type circuit breaker, such an early opening and early closing auxiliary switch will be an aid in preventing the waste of air. Heretofore, in order to open the trip circuit during the opening stroke of the circuit breaker at a point entirely independent of the closing of the trip circuit during the circuit breaker closing stroke, a combination of switches and sometimes relays, have been used which were not only cumbersome, but to a large extent were not very reliable.

Accordingly, it is an object of my invention to provide a new and improved auxiliary switch for an electric circuit breaker which is opened or closed in response to the opening and closing of the circuit breaker.

It is another object of my invention to provide a new and improved auxiliary switch for an electric circuit breaker which opens the trip circuit at a point during the opening stroke of the circuit breaker independently of the point

during the closing stroke of the circuit breaker at which the auxiliary switch closes the trip circuit of the circuit breaker.

Further objects and advantages of my invention will become apparent as the following description proceeds and the features of novelty which characterize my invention will be pointed out with particularity in the claims annexed to and forming a part of this specification.

10 For a better understanding of my invention, reference may be had to the accompanying drawings in which Fig. 1 is a partly diagrammatic layout of an electric circuit breaker and a control system therefor embodying my invention, 15 Fig. 2 illustrates a portion of the apparatus and system of Fig. 1 showing a different operating position thereof, and Figs. 3 and 4 are diagrammatic layouts similar to Figs. 1 and 2 respectively illustrating a modification of my invention.

20 Since my invention is applicable to any electric circuit breaker, single phase or polyphase, I have chosen to illustrate it as applied to an electric circuit breaker 10 schematically illustrated as a single pole breaker for controlling the flow of power between two circuits 11 and 12 which have been illustrated as single phase circuits. It should be understood that circuits 11 and 12 and circuit breaker 10, might equally well 25 be polyphase. Circuit breaker 10 has been illustrated as a latched closed circuit breaker including a latch 13 for holding circuit breaker 10 closed. Latch 13 may be operated by means of a trip coil 14. In series with trip coil 14 are the 30 contacts 15 of my new and improved auxiliary switch, generally indicated at 16 and to be described in greater detail hereinafter.

35 Circuit breaker 10 is illustrated as being provided with a closing winding 17 connected across a source of control potential 18 through a manually operable closing switch 19. In order to simplify the disclosure I have not illustrated the circuit for controlling the automatic reclosing of circuit breaker 10 upon opening thereof. 40 However, such automatic reclosing controls are well-known in the art and any such suitable control may be provided.

45 The trip circuit including trip coil 14, and the contacts 15 of auxiliary or a switch 16 are connected across a source of control potential either through a manually operable opening switch 20, or through the contacts 21 of fault responsive relay 22 which has a winding 23 thereof energized in response to the current flowing in circuits 11 and 12 by virtue of a current transformer 24.

Since the contacts 21 are usually rather delicate although they can close the trip circuit, are incapable of opening the trip circuit without damage thereto, some form of sealing action is usually employed. As illustrated in Fig. 1 this sealing action comprises a separate winding 25 on fault responsive relay 22 which winding is associated with a separate magnetic structure. This winding 25 is energized through the contacts 21 of fault responsive relay 22 so that whenever fault responsive relay 22 is energized by virtue of an abnormally high current flowing in the windings of current transformer 24, the contacts 21 are closed by a contact controlling member 26 and winding 25 is energized to maintain these contacts in the closed position until the contacts 15 of the auxiliary switch 16 are opened. Fault responsive relay 22 is often provided with some time delay means to prevent high speed closing thereof whereby transients will not cause false tripping of circuit breaker 10. As a practical matter the contacts 21 also require some time to open and although that time is maintained as small as possible, it nevertheless may be sufficient to cause difficulty in connection with high speed reclosing type circuit breakers unless resetting of fault responsive relay 22 is permitted early during the opening stroke of circuit breaker 10.

Auxiliary switch 16, embodying my invention, is very simple and compact and yet provides an arrangement whereby the trip circuit is deenergized during the opening stroke of the circuit breaker at a point independent of the point during the closing stroke of the circuit breaker when the trip circuit is completed insofar as the contacts 15 are concerned.

As illustrated in the drawings, auxiliary switch 16 comprises a member 27, pivotally mounted at 28. Pivotal movement of member 27 in response to opening and closing movements of circuit breaker 10 is obtained by means of a gear 29 which engages a rack 30 on the operating rod of circuit breaker 10. Opening or closing of circuit breaker 10 will cause gear 29 to rotate in a clockwise or counterclockwise direction respectively. One end of lever 27 is connected by means of a link 31 and a crank 32 with the shaft 33 to which gear 29 is attached so that opening and closing of circuit breaker 10 will cause member 27 to rotate about pivot 28. The other end 27' of pivotally mounted lever 27 is adapted to engage a pivotally mounted contact controlling member 34 which is normally biased to the open position indicated in Fig. 2 by means of a spring 35. A suitable stop 36 limits the opening movement of switch or contact controlling member 34. As long as the end 27' of lever 27 engages the switch or contact controlling member 34 as indicated in Fig. 1, the contacts 15 of auxiliary switch 16 are held closed. Upon opening of circuit breaker 10 lever 27 begins to rotate about pivot 28 in a counterclockwise direction, thereby permitting early opening of contacts 15 of auxiliary switch 16 as is indicated in Fig. 2.

Although the arrangement described thus far provides early opening of contacts 15 of the auxiliary switch 16 during the opening stroke of circuit breaker 10, this arrangement alone would provide late closing of the contacts 15 during the closing stroke of circuit breaker 10 which, as has been pointed out above, would be undesirable. In order to control the closing of contacts 15 at a point of the breaker stroke which is independent of the opening point of these con-

tacts, I provide a pivotally mounted dog or member 37, which is pivotally mounted to the end 27' of lever 27 as indicated at 38. A suitable spring 39 which is a lighter spring than spring 35 mentioned above, biases dog 37 in a counterclockwise direction against an adjustable screw 41 in stop member 40. During the opening stroke of circuit breaker 10 dog 37 rotates in a clockwise direction since spring 39 is insufficient to maintain switch controlling member 34 closed against the action of spring 35. During the closing stroke of circuit breaker 10, however, as may be clearly seen from Fig. 2 dog 37 engages switch controlling member 34 early during the closing stroke and causes contacts 15 to be closed since the adjustable stop comprising screw 41 prevents relative rotation between dog 37 and member 27. With this arrangement the surface 34' of switch controlling member 34 engaged by the end 27' of lever 27, controls the point where contacts 15 are opened with reference to the circuit breaker opening stroke, while the length of surface 37' of dog 37, controls the point at which the contacts 15 are closed with reference to the circuit breaker closing stroke. By changing the relation of these surfaces and in extreme cases the gear connecting auxiliary switch 16 with the operating mechanism of circuit breaker 10, it is possible to obtain any practical variation between the point of make and the point of break of contacts 15 that may be required.

In view of the detailed description included above, the operation of the auxiliary switch of my invention will be obvious to those skilled in the art. In Fig. 1 the circuit breaker is closed and the auxiliary switch contacts 15 are also closed. Upon opening the breaker, gear 29 rotates in the direction of the arrow indicated in Fig. 1 to cause member 27 to rotate in a counterclockwise direction. Since dog 37 which is pivoted on lever 27 can rotate in clockwise direction in Figs. 1 and 2 it will have no influence in holding switch controlling member 34 in a position to maintain contacts 15 closed, but instead will collapse allowing contacts 15 to open as soon as the surface 34' is free of the end of lever 27.

Referring to Fig. 2 showing the circuit breaker 10 and consequently the auxiliary switch 16 in the open position, closing of circuit breaker 10 will cause gear 29 to rotate in the direction of the arrow indicated in Fig. 2. Lever 27 first moves in a counterclockwise direction and when this motion has progressed to a predetermined point it rotates in a clockwise direction. As this clockwise motion continues, dog 37 engages the surface 34' of contact controlling member 34 so as to close contacts 15. Further clockwise rotation of lever 27 carries dog 37 clear of the surface 34' but the end 27' of lever 27 then maintains the contacts 15 in the closed position.

Although I have disclosed my invention in Figs. 1 and 2 as employing a gear 29, a rack 30 and a crank 32, it should be understood that my invention might be applied to a circuit breaker without these members. Accordingly in Figs. 3 and 4 I have disclosed my invention in a similar manner as in Figs. 1 and 2 respectively with the corresponding parts thereof designated by the same reference numerals. However, gear 29, rack 30, crank 32 and shaft 33 have been omitted and instead the end of link 31 remote from member 27 is pinned directly to the operating rod of circuit breaker 10 as indicated at 42. The aux-

iliary switch 16 is identical with that shown in Figs. 1 and 2 except that the entire switch and mechanism is rotated 180 degrees about a horizontal axis.

The operation of the arrangement indicated in Figs. 3 and 4 will be obvious in view of the detailed description included above.

Although I have disclosed dog 37 as pivotally mounted on member 27 it will be obvious that it might be pivotally mounted on member 34 instead. Also, although I have disclosed auxiliary switch 16 as one which opens the circuit when the circuit breaker is opened, it might equally well be one which closes the circuit when the circuit breaker is opened.

It should be understood that my invention is not limited to the specific details of construction and arrangement herein illustrated and that changes and modifications may occur to one skilled in the art without departing from my invention and I, therefore, aim in the appended claims to cover all such changes and modifications as fall within the true spirit and scope of my invention.

What I claim as new and desire to secure by Letters Patent of the United States is:

1. An auxiliary switch for performing a controlling function for a circuit breaker which switch opens and closes in response to the operation of said circuit breaker, comprising a pivotally mounted member movable in response to opening and closing movements of said circuit breaker, contact controlling means, and means including a pivoted element arranged on said pivotally mounted member so as to cause said contact controlling means to operate early during both the closing and opening strokes of said circuit breaker.

2. An auxiliary switch for controlling the trip circuit of a circuit breaker which switch is open when the circuit breaker is open and closed when the circuit breaker is closed, comprising a pivotally mounted member movable in response to opening and closing movements of said circuit breaker, contact controlling means, and means including a pivotally mounted dog on said pivot-

ally mounted member for causing said contact controlling means to operate early during both the closing and opening strokes of said circuit breaker.

3. An auxiliary switch for performing a controlling function for a circuit breaker which switch opens and closes in response to the operation of said circuit breaker, comprising a pivotally mounted member movable in response to opening and closing movements of said circuit breaker, contact controlling means, and a pivotally mounted dog on said pivotally mounted member for causing said contact controlling means to operate at a point during the opening stroke of

10 said circuit breaker, independently of the point during the closing stroke of said circuit breaker at which said contact controlling means is operated.

4. An auxiliary switch for controlling the trip 20 circuit of a circuit breaker which switch is open when the circuit breaker is open and closed when the circuit breaker is closed comprising a pivotally mounted member movable in response to opening and closing movements of said circuit breaker,

25 contact controlling means, and a pivotally mounted dog on said pivotally mounted member for causing said contact controlling means to open at a point during the opening stroke of said circuit breaker, independently of the point during the closing stroke of said circuit breaker at which said contact controlling means is closed.

5. An auxiliary switch for controlling the trip 30 circuit of a circuit breaker which switch is open when the circuit breaker is open and closed when the circuit breaker is closed comprising a pivotally mounted member movable in response to opening and closing movements of said circuit breaker, contact controlling means, and means on 35 said pivotally mounted member for causing said contact controlling means to open at a point during the opening stroke of said circuit breaker, independently of the point during the closing stroke of said circuit breaker at which said contact controlling means is closed.

HAROLD N. SCHNEIDER.
